TRAFFIC SIGNAL SYSTEM CONTROL CABINET

John W. Hodge, Moline, Ill., assignor to Eagle Signal Corporation, Moline, Ill., a corporation of Massachusetts

Application May 31, 1955, Serial No. 36,294

Term of patent 14 years

(Cl. D26—5)

The figure is a perspective view of a traffic signal system control cabinet, showing my new design.

The back of the cabinet is plain and the side opposite to that shown is similar to the side shown.

I claim:

The ornamental design for a traffic signal system control cabinet, as shown and described.
